UNITED STATES PATENT OFFICE.

CHARLES FRED REICHSTEIN, OF MEDFORD, OREGON.

SAWING MACHINE.

Application filed March 15, 1921. Serial No. 452,413.

To all whom it may concern:

Be it known that I, CHARLES FRED REICHSTEIN, a citizen of the United States, and a resident of Medford, in the county of Jackson and State of Oregon, have invented certain new and useful Improvements in Sawing Machines, of which the following is a specification.

My invention relates generally to sawing machines and particularly, although not necessarily, to machines for sawing fire wood.

Fire wood is generally cut in four feet lengths and sold by the cord, it being necessary to saw the timber into the proper lengths to fit a particular stove. The wood is generally sawed in either twelve or sixteen inch lengths, and it is the purpose of my invention to provide a sawing machine which is adjustable to saw the sticks into twelve or sixteen inch lengths although it is to be understood that the machine can be so designed and adjusted as to cut the sticks into blocks of any requisite stove length.

It is also a purpose of my invention to provide a sawing machine which is capable of being operated by a single individual, and in which novel means is provided for adjusting the saws to vary the length of the blocks cut, and to provide means for positively maintaining the sticks against turning or twisting during the interval in which they are in engagement with the saws so that the proper and accurate cutting of the blocks is insured.

I will describe one form of sawing machine embodying my invention and will then point out the novel features thereof in claims.

In the accompanying drawings:

Figure 1 is a view showing in side elevation one form of sawing machine embodying my invention.

Figure 2 is a top plan view of Figure 1 partly broken away.

Figure 3 is a top plan view of the table comprised in the machine with portions thereof broken away.

Figure 4 is a vertical sectional view of the machine shown in Figure 2.

Figure 5 is a vertical sectional view taken on the line 5—5 of Figure 4.

Figure 6 is a vertical sectional view through one of the adjustable rotary saws shown in the preceding views.

Figure 7 is a vertical sectional view taken on the line 7—7 of Figure 6.

Similar reference characters refer to similar parts in each of the several views.

Referring specifically to the drawings and particularly to Figure 1, my invention in its present embodiment is shown as positioned on a truck which permits of the ready removal of the machine from place to place to facilitate the cutting of the cords. The truck is designated generally at T and includes a bed 13 from which extend uprights 16 for supporting a table designated generally at B in inclined position thereon. As illustrated to advantage in Figure 3, the table comprises longitudinally extending beams 17 connected by transverse beams 18. Supported upon the beams 17 and 18 are hingedly disposed partitions 19 arranged to provide a longitudinally extending slot in 75 which endless conveyors designated at C are adapted to work. The conveyors C comprise in the present instance endless chains 20 trained about sprockets 21 fixed to shafts 22 journaled in the outer ends of relatively short beams 23 secured to the beams 18. The chains 20 carry triangular shaped projections 24 at regular spaced intervals throughout their length, such projections serving as followers for effecting the movement of the sticks of wood over the table.

As shown in Figure 3, shafts 25 and 26 are journaled in suitable bearings supported upon the beams 17, such shafts being arranged transversely of the table and having 90 one of their ends provided with pulleys 27 and 27^a, respectively, to which power is adapted to be applied as will be hereinafter described. The shaft 26 has keyed thereto at a point intermediate its ends a rotary 95 saw S, while the shaft 25 carries two rotary saws S' and S^a which are keyed to the shafts in the manner shown in Figures 6 and 7 to permit of the rotation of the saws with the shaft or to allow of a longitudinal movement of the saws on the shaft in order that they may occupy various spaced positions with relation to each other. As shown in Figures 6 and 7, the saw S' or S^a is secured on a hub 28 by means of threaded collars 29. The hub 28 is slotted longitudinally on its inner side to receive a key 30, and the adjacent portion of the shaft 25 is likewise slotted to receive such key, it being noted that the key is of sufficient length to 110

permit of the necessary longitudinal movement of the hub 28 thereon while at the same time locking the hub and consequently the saw to the shaft for rotation therewith.

5 As shown in Figure 3, the saws are arranged to project from the upper side of the table B between the conveyor belts C with the saws S' and S² spaced apart and the saw S arranged in the rear of these 10 saws and on a line between the saws. The relative position of the saws S' and S² are adapted to be varied for the cutting of blocks of different lengths by means of yokes K and K' which are slotted to accommodate the saws S' and S² and which embrace the hubs 28 and collar 29 so that when moved laterally a corresponding movement of the saws upon the shaft 25 is effected. As shown in Figure 5, the yokes K 15 and K' are mounted for lateral sliding movement in slots 31 formed in two of the adjacent cross beams 18, the opposite ends of the yokes being provided with suitable tongues 32 which slidably fit within these 20 slots. Lateral movement of the yokes is effected through the medium of the bar 33 which is connected to the yokes by toggle links 34, such links being arranged in pairs with the links of each pair pivoted to the 25 bar at a common point at one end and to the yokes K and K' at a corresponding point at the other end. The toggle links 34 of each pair occupy divergent positions with respect to each other so that by moving the 30 bar 33 longitudinally a spreading or contracting of the links is effected according as the bar is moved in one direction or the other and thereby effecting the movement of the yokes K and K' toward or away from 35 each other. Movement of the bar 33 is effected by means of a lever 35 fulcrumed upon the table at the point indicated at 36 and pivotally connected at one end of the bar 33 at a point indicated at 37. The free 40 end of the lever 35 projects from the side of the table so that it can be readily manipulated by the operator. This end of the lever is adapted to be engaged by a latch 38 for maintaining the lever in that position where- 45 in the yokes K and K' occupy their greatest spaced position. The yokes are normally urged toward each other by means of coiled contractile springs 39 connected to the confronting sides of the yokes in the manner 50 shown in Figures 3 and 5.

Referring now to Figures 1, 2 and 4, I have here shown means for maintaining the sticks of wood in immovable engagement with the followers 24 during the interval 55 in which the sticks are engaged by the rotary saws S, S' and S². This means in the present instance comprises a pair of channeled members M and M' which, as shown in Figure 2, are positioned above the table T and 60 between the saws S, S' and S² so that cer-

tain of the conveyor belts C are free to move within the channels of the members. The upper ends of the members M and M' are pivotally and slidably connected to a cross bar 40 mounted in standards 41 and extends 70 transversely of the table at a point adjacent its upper end. This connection is effected through the medium of arms 42 provided with T-heads 43 which are pivotally mounted in ears 44 secured to the upper ends of 75 the members M and M'. The arms 42 are slidably fitted within couplings 45 which latter serve to connect the several sections of which the cross bar 40 is composed. These 80 couplings 45 are mounted for movement upon the cross bar 40, and being slidably associated with the arms 42, it will be clear that the members M and M' are capable of longitudinal sliding movement upon the table. By virtue of the pivotal connection 85 between the arms 42 and the members, the latter are capable of vertical swinging movement, but are locked against lateral swinging movement so that they occupy the same 90 position with respect to the saws and conveyor belts at all times and thus permit the proper operation of the latter. The lower ends of the members M and M' are beveled as indicated at 46 in Figure 1, and these 95 beveled ends carry hingedly supported bearings 47 in which shafts 48 are journaled. The opposite ends of the shafts 48 carry rollers 49 that are adapted to be projected into the path of movement of the sticks of wood so as to guide the sticks into engagement with the beveled ends of the members and ultimately beneath the members where they are maintained during the interval in 100 which the several saws engage the sticks. Owing to the manner of supporting the members M and M' it will be clear that the weight of such members is free to act upon the sticks of wood as they are successively delivered to the saws, and under such action the sticks are maintained in immovable engagement with the conveyor belts so that it is impossible for them to twist or turn while 105 they are being sawed.

For the purpose of preventing lateral movement of the lower ends of the members M and M', I provide a plate 50 hingedly supported on the round portion 51^a of a frame. The frame includes a horizontal portion 51 which extends above and across the table in the manner shown in Figure 2 110 and a vertical portion 52 formed at one end of the horizontal portion and extending downwardly and secured to the side of the table. The plate 50 is normally supported in inclined position with its lower edge 115 provided with extensions 50^a which are interposed between each pair of rollers 49 so as to engage the rollers when the members M and M' tend to move laterally and thus to lock the members against such movement. 120

This arrangement in conjunction with the means for supporting the upper ends of the members insures that the members will at all times occupy a predetermined position transversely of the table and to thereby permit of the proper operation of the saws and conveyor belts.

Any suitable means may be provided for continuously driving the conveyor belts and 10 rotary saws, I having in the present instance provided an internal combustion engine E mounted on the bed 15 of the truck. The engine is adapted to be operatively connected to the saws by means of a pulley P keyed 15 to the engine shaft 53 and about which is trained a belt 54. This belt 54 is also trained about the pulleys 27 and 27^a so as to effect rotation of the saws S, S' and S² in the direction of the arrows in Figure 1. 20 Between the pulley P and the pulleys 27 and 27^a, the belt 54 is engaged by a tensioning device which in the present instance comprises a pulley 55 journaled on the upper end of an arm 56 hingedly supported 25 at the point indicated at 57. A cable 58 is connected to the arm 56 and trained about a shaft 59 which is adapted to be operated by a crank 60 for moving the arm so as to cause the pulley to tighten or loosen the belt 30 54 and to thereby operatively connect or disconnect the pulley P to or from the pulleys 27 and 27^a. The shaft 59 can be locked so as to maintain the pulley 55 in operative position by means of a ratchet wheel 61 35 which is engaged by a spring pressed pawl 62. The several conveyor belts C are adapted to be continuously rotated so that their upper stretches move upwardly of the inclined table by means of a pulley 63 fixed 40 to one end of the upper shaft 22. The pulley 63 is operatively connected to the engine shaft 53 by means of a belt 64 which is twisted intermediate its looped ends so as to effect rotation of the pulley 63 in the direction 45 of the arrow in Figure 1. The belt 64 is also engaged by a tensioning device which comprises a grooved pulley 65 pivotally supported upon an arm 66 which is engaged by a spring 67 for normally maintaining the 50 pulley in tensioning position with respect to the belt so as to operatively connect the shaft 22 to the shaft 53. This tensioning device can be actuated by the operator while standing at the lower end of the table 55 by means of a flexible cable 68 which is trained over a pulley 69 supported on one edge of the table. The upper end of the cable is connected to the arm 66 while its lower end is adapted to be disposed at the 60 lower end of the table within easy reach of the operator. Staples 70 are arranged at intervals along the edge of the table and through which the cable 68 is adapted to be trained so as to properly support the cable 65 for operation.

The operation of the sawing machine is as follows: With the engine E operating and the pulleys 55 and 65 in tensioning position, the upper stretches of the conveyor belts move upwardly of the table, while the several saws are rotated so that their projecting portions move in a direction opposite to the direction of movement of the conveyor belts. If a stick of wood is now placed upon the lower end of the table and transversely of the conveyor belts, it will be engaged by the followers 24 and thus carried upwardly of the table in the direction of the saws where it first engages the several rollers 49 and is thus guided into engagement with the beveled ends 46 of the members M and M'. The beveled edges serve to elevate the members M and M' as the stick of wood passes beneath such members, and by virtue of the weight of the members and the frictional contact between the wood and the members, the stick of wood is immovably held in engagement with the conveyor belts so that when the saws S' and S² engage the stick of wood it will not twist or turn wherefor the saws will effect a clean cutting of the wood. By virtue of the arrangement of the saws S' and S², it will be clear that the stick of wood is cut at two different points within its length so as to divide the stick into three 95 blocks. These blocks under the action of the conveyor belts are carried upwardly of the table where the saw S engages the center block and thus cuts the same into two small blocks. This center block is also immovably held against twisting or turning because of the fact that the members M and M' are still in engagement with the wood, and remain in contact therewith until all of the blocks have passed out of engagement with the saws. The several blocks are ultimately deposited from the upper end of the table into any suitable receptacle arranged therebeneath. Should the sticks of wood tend to jam between the members M and M' and the table or conveyor plate, it will be clear that by virtue of the mounting of the members they are free to move upwardly of the table thus releasing the wood and permitting of the proper operation of the conveyor belts. Because of the inclination of the members M and M' they will return to normal position after all the blocks have passed from beneath the same so as to be in operative position for succeeding 110 blocks introduced on the conveyor belts at the lower end of the cable.

As previously stated, this sawing machine is primarily designed for the cutting of sticks of fire wood which are usually four 125 feet in length. These sticks are generally cut in blocks of twelve or sixteen inches in length. With the saws S' and S² in the position shown in Figure 2, they are adapted to coact with the saw S to cut the sticks of 130

wood into four twelve inch blocks. When it is desired to divide a strip of wood into three sixteen inch blocks, the saws S' and S^2 are moved outwardly from each other by a 5 manipulation of the lever 35 in the manner previously described, and with the saws in this expanded position it will be clear that when a stick of wood is placed so as to be engaged by the saws S and S' or S^2 and S , 10 it will be cut into three blocks of equal length, it being understood that during this operation the saw S' or S^2 remains idle.

From the foregoing operation taken in conjunction with the accompanying drawings, 15 it will be manifest that I have provided a sawing machine which is operable to cut sticks of wood into various lengths by an adjustment of certain of the saws, and that such adjustment can be effected without 20 the necessity of disassociating any part of the machine and while the machine is in operation. Furthermore, the machine includes positive means for maintaining the sticks of wood in operative relation to the saws 25 and against turning or twisting so that the proper cutting of the wood by the saws is insured.

Although I have herein shown and described only one form of sawing machine

embodimenting my invention, it is to be understood that various changes and modifications may be made herein without departing from the spirit of the invention and the spirit and scope of the appended claims.

What I claim is:

1. A sawing machine comprising, a table, conveyor belts movable over the table, a shaft journaled on the table, rotary saws mounted for longitudinal movement on said shaft but rotatable therewith, yokes mounted for sliding movement on the table and embracing said saws, a bar between the saws, links connected to said yokes and bar, springs connecting said yokes for normally urging the yokes toward each other, and a 40 lever connected to said bar for manually actuating the same.

2. In a sawing machine, a pair of rotary saws mounted for lateral movement with respect to each other, yokes embracing the 50 saws also mounted for sliding movement, toggles connected to the yokes, springs connecting the yokes for normally urging the same toward each other, and manually operable means for simultaneously actuating 55 the toggles against the action of said springs.

CHARLES FRED REICHSTEIN.
